UNITED STATES PATENT OFFICE

1,928,557

KNITTING MACHINE

Edward J. Crane, Lexington, N. C., assignor to
Mountcastle Knitting Co., Inc., Lexington,
N. C., a corporation of North Carolina

Application January 13, 1931. Serial No. 508,529

15 Claims. (Cl. 66—40)

This invention relates to mechanism for producing designs on knitted fabric by a plating process. The invention relates particularly to an attachment which is adapted to be applied to a seamless hosiery knitting machine.

The attachment forming the subject of the present application has been designed for and is shown as being applied to a "Banner" machine as evolved from the fundamental machine disclosed in U. S. Letters Patent No. 933,443, dated September 7, 1909, the present machine comprising various improvements covered by subsequent patents assigned to the Hemphill Co., Pawtucket, Rhode Island.

15 The object of the present invention is to provide an attachment adapted to be applied to a knitting machine for the purpose of manipulating predetermined needles, or groups of needles, whereby such needles will be actuated in a manner to receive a plating, or design-forming, thread in addition to the thread, or threads, employed in the formation of a foundation fabric.

In the present instance, an attachment is disclosed as being applied to a machine capable of producing designs by a reverse plating process, the attachment being so constructed, and operated in such a manner in conjunction with the other elements of the machine, as to produce on any desired part of the design formed by the 25 normal reverse plating a superposed design such as would be produced by an ordinary plating process.

The reverse plating design, in the present case, is produced by jacquard mechanism forming no 30 part of the present invention, whereas the superposed plated design is produced by mechanism constituting the present invention, which will be 35 fully disclosed hereinafter, reference being had to the accompanying drawings, of which:

40 Fig. 1 is a side elevation of a conventional type of circular knitting machine, showing the mechanism that constitutes the present invention as being applied thereto;

45 Fig. 2 is a front elevation of the mechanism shown in Fig. 1;

Fig. 3 is a plan view;

50 Fig. 4 is a fragmentary sectional elevation drawn to an enlarged scale and showing the attachment forming the subject of the present application in co-operative relation to other elements of the machine;

55 Fig. 5 is a sectional plan view taken on the line 5—5, Fig. 4;

Fig. 6 is a detached perspective view of the at-

tachment forming the subject of the present invention;

Figs. 7, 8 and 9 are perspective views of needle-jacks used in conjunction with the attachment shown in Figs. 5 and 6;

60 Fig. 10 is a flat development of the needle cylinder showing the needles co-operating with the attachment cams and the regular stitch cams of the machine;

Figs. 11, 12 and 13 illustrate details of the 65 present invention;

Fig. 14 is a plan view of the regular stitch cam assembly of the machine;

Fig. 15 is a sectional elevation taken on the 70 line 15—15, Fig. 14;

Fig. 16 diagrammatically illustrates the form of superposed design that would be produced by the arrangement of machine disclosed in the other figures of the drawings;

Fig. 17 diagrammatically illustrates the arrangement of needle-controlling jacks for producing the design shown in Fig. 16;

Fig. 18 shows another form of design that may be produced by use of the attachment forming the subject of the present invention;

75 Fig. 19 shows the arrangement of needle jacks for producing the design shown in Fig. 18;

Figs. 20 and 21 illustrate still other forms of 80 designs that may be produced; and

Fig. 22 illustrates the arrangement of needle 85 jacks for producing the design shown in Figs. 20 and 21.

The machine that has been chosen to illustrate the operation of the attachment forming the subject of the present invention comprises a main 90 frame 1 mounted upon supporting legs 2, 2, and having a top plate or flat table 3 in which is rotatably mounted a needle cylinder 4.

The cylinder 4 is adapted to be continuously 95 rotated, or oscillated, by means of a beveled gear-ring 5 that is suitably secured to the lower end of the cylinder 4. The gear-ring 5 meshes with a beveled gear 6 which is mounted on a horizontal shaft 7. The shaft 7 is suitably journaled in the main frame 1 of the machine.

100 Continuous rotation of the cylinder 4, as effected during the formation of the leg and foot portions of a seamless circular knit stocking, and oscillation of the cylinder 4, as effected during the formation of the heel and toe pockets of the seamless circular knit stocking, are produced at the proper times by mechanisms shown and described in the above mentioned patent.

105 The needle cylinder 4 is grooved in the usual manner, as indicated at 8, for the reception of 110

needles 9 having butts 10 which are acted upon by the regular stitch-forming cams 11, 12, 13, 14 and 15 of the machine.

In producing the courses of stitches constituting the foundation fabric in the form of leg, foot, heel and toe portions of the stocking, the cams 11, 12, 13 and 14 are assembled on a block 16 mounted on a platform 17 disposed above and spaced from a table 3 of the machine.

10 Pivotedly mounted on the block 16, adjacent the cams 13 and 14 respectively, are spring-pressed needle pickers 18 and 19 for moving certain of the needles out of action during the formation of the heel and toe of the stocking.

15 Secured to each of a predetermined number of needles 9, which have been selected for the formation of a design in accordance with the principles of the present invention, and mounted in the lower ends of the needle slots 8 in the cylinder 4 20 are needle-controlling elements in the form of jacks or extensions 20. Each needle extension 20 is provided with a radially extending butt 21 operable longitudinally of the cylinder 4 in the space between the table 3 and the relatively elevated cam-supporting platform 17.

As shown in Figs. 7, 8 and 9, the butts 21 of the needle extensions 20 are of various lengths, as illustrated respectively at 21a, 21b and 21c.

25 Mounted, in the present instance, on the ring 30 22 that rotatably maintains the gear-ring 5 in place and between the upper face of the table 3 and the lower side of the cam-supporting platform 17 is a block 25 which constitutes a supporting base for the elements constituting the attachment forming the subject of the present instance.

30 Slidably mounted in the supporting block 25 is a cam 26 which is inclined in a direction circumferentially of the needle cylinder 4 and which is adapted to be moved radially with respect to the needle cylinder 4, to engage or to be engaged by the butts 21 of the needle extensions 20 of those of the needles which are adapted to produce the superposed design on the knitted fabric.

Upon relative rotation being effected between 45 the needle cylinder 4 and the cam 26 the needle-extension butts 21 will ride on the upper inclined surface 27 of the cam 26, in the manner illustrated in Figs. 4 and 10, to elevate certain of the predetermined needles above the normal line *a*, formed by the tops or hook ends of the needles when the needles are in the position to receive the regular foundation forming thread or threads *x*, *y*, to a relatively higher level *b*, so that the raised needles, upon which the superposed design is to be formed, may receive a plating thread *z* as such thread extends between a thread clamp 30 and a thread guide 31, as illustrated in Figs. 4 and 10.

50 In order to give contour to the superposed design, the needle-raising cam 26, as above noted, is adapted to be moved from a normal inoperative position outside the path of the outer end of the longest needle-extension butt 21c radially inward with respect to the needle cylinder 4 to be engaged by any desired group of the needle-extension butts 21a, 21b and 21c. If all of the predetermined groups of needles are to be raised the needle-raising cam 26 will be moved toward the needle cylinder 4 in such close proximity to the periphery thereof as to be engaged by all the butts 21a, 21b and 21c.

55 In other cases, the cam 26 is moved to such a position with respect to the needle cylinder 4 that the said cam will be engaged by only the intermediate butts 21b and the longest butts 21c, the short butts 21a passing the cam 26 with-

out being engaged thereby, as illustrated in Fig. 10.

In other cases, during the formation of a predetermined design, the cam 26 may be moved to such a position with respect to the needle cylinder 4 as to be engaged by only the longest of the butts 21c, the short and intermediate butts 21a and 21b respectively passing by the cam 26 without being engaged thereby.

60 In other cases, it may be desirable to raise only those needles equipped with the short butts 21a, whereupon the cam 26 will be moved toward the needle cylinder in a manner to be engaged by all the butts 21a, 21b and 21c. In such a case a trailing cam 32 is provided directly following the raising cam 26 and adapted to be moved, like the cam 26, from an outer inoperative position, radially inward with respect to the needle cylinder 4. The trailing cam 32 is provided with an inclined surface 33 which is adapted to engage the upper edges of certain of the butts 21 on the needle-extensions 20 to lower the needles controlled thereby, after such needles have been raised by the raising cam 26, so that such needles will not take the design-forming thread *z*.

65 Obviously, by moving the trailing cam 32 100 radially with respect to the needle cylinder 4 to a position just beyond the outer edges of the short needle butts 21a, these needle-extension butts will pass by the trailing cam 32 leaving the needles controlled thereby in an elevated position to take the thread *z*, while the needles having the intermediate and longest butts 21b and 21c respectively will engage the inclined surface 33 105 of the trailing cam 32 and thereby be lowered to the normal line *a* so that these needles will 110 not take the thread *z* as they pass the thread guide 31.

70 By moving the trailing cam 32 still further away from the needle cylinder 4 the intermediate butts 21b will be caused to miss the lowering 115 cam 32 and thereby remain in their elevated thread-taking position, while the longest butts 21c will be engaged by the lowering cam 32 and be thereby lowered to the position *a* wherein they 120 will not take thread.

75 From the above, it will be obvious that by manipulating the cams 26 and 32 any desired sets of the predetermined groups of needles which are adapted to form a superposed design on the foundation fabric may be caused to take the 125 design-forming thread *z* as these needles pass the thread guide 31, upon relative rotation being effected between the needle cylinder 4 and the thread guide 31 and the cams 26 and 32.

80 The cams 26 and 32 are so arranged as to 130 be operated independently or simultaneously. For example, the cams may be moved in unison with the front face 34 of the lowering cam 32 spaced outwardly from the front face 35 of the raising cam 26 to the extent of the difference 135 between the lengths of the intermediate butts and the longest butts, or the intermediate butts and the shortest butts.

85 As a result of moving the two cams in unison 140 inwardly toward the needle cylinder 4, the longest butts 21c would first engage the raising cam 26 and thereby elevate the needles controlled thereby to the thread-taking position, the front face 34 of the lowering cam 32 being spaced behind the front face 35 of the raising cam 26 145 to such an extent that the outer ends of the long butts 21c will not engage the lowering cam 32.

90 Upon moving the cams 26 and 32 in unison toward the needle cylinder 4 a distance corre- 150

sponding to the difference between the length of the intermediate butts and the long butts, the needle-extensions provided with the long and intermediate butts respectively will be raised by 5 said butts riding up on the raising cam 26. However, the lowering cam 32 having been moved toward the needle cylinder 4 will now be engaged by the long butts 21c and the needles controlled thereby will be lowered out of the thread-taking 10 position, leaving only those needles that are provided with the intermediate butts in a position to take thread.

A still further movement of the cams 26 and 32 in unison toward the needle cylinder 4 will 15 bring the raising cam 26 into a position to engage all three sets of butts, that is, the butts 21a, 21b and 21c. The lowering cam 32 having been moved a corresponding distance will then be in a position to engage the intermediate butts 21b 20 and the long butts 21c, leaving only those needles controlled by the short butts 21a in a position to take thread from the thread guide 31.

Upon reversing the movement of the cams 26 and 32 in unison the cam 26 will be moved out 25 of the path of the short butts 21a, consequently the needles associated with the short butts 21a will remain in the lower position and will not take thread. The needles having the intermediate butts 21b and those having the long butts 21c 30 will, however, be raised by the cam 26, and those having the long butts 21c will be engaged by the lowering cam 32, consequently leaving only the needles controlled by the intermediate butts 21b in the elevated position to take thread from 35 the thread guide 31.

Further movement of the cams 26 and 32 outwardly with respect to the needle cylinder 4 will cause only the needles controlled by the long butts 21c to be raised by the raising cam 26 to 40 an elevated position to take thread from the thread guide 31.

In following out the operations just described with an arrangement of butts, such as illustrated in Fig. 17, a design, such as illustrated in Fig. 45 16, will be superimposed upon the foundation fabric.

By using a butt set-up, such as illustrated in Fig. 17 and Fig. 19 and by leaving the lowering cam out of action, a design, such as shown in Fig. 50 18, may be provided.

By the use of a butt set-up, such as illustrated in Fig. 22, which is the reverse of that shown in Figs. 17 and 19, and by leaving the lowering cam out of action, a solid diamond-shaped design, such as illustrated in Fig. 20, may be provided, 55 and by the use of a set-up, such as illustrated in Fig. 22, and moving the lowering cam in unison with the raising cam, in the manner above noted, a design, such as illustrated in Fig. 21, may be 60 provided.

From the above, it will be obvious that by arranging the long, intermediate and short butts in various relation to each other in the cylinder 4 and by operating the raising and lowering cams 26 and 32 independently or in unison a large variety of designs may be produced on the fabric without interfering with the normal operation of the machine whether the machine is adapted 65 to produce only plain foundation fabric or a fabric having primary designs formed thereon by a reverse plating operation.

As shown in Fig. 6, the cam 26 is provided with a stem 36 rectangular in cross-section and 70 slidably mounted in the supporting block 25. The block 25 is provided with angularly dis-

posed guide slot 37 adapted to receive and guide the stem 36 of the cam 26, said slot 37 having a lateral extension 38 adapted to receive the body portion of the cam 26.

The block 25 is also provided with a groove 39 adapted to receive and slidably support the lowering cam 32. The lowering cam 32 is provided with a vertically extending pin 40 passing through a slot 41 formed in a cap 42, which maintains the cam 32 in its guideway 39 and in turn is secured to the block 25 by screws 43.

Radial movement of the lowering cam 32 is effected by a lever 45 pivoted at 46 to a foot portion 47 of the block 25, by which the block is secured in place on the ring 22, by means of screws 48. The lever 45 is slotted at one end, as illustrated at 49, to operatively receive the actuating stud of the cam bar 32.

Pivotedly attached to the outer end of the lever 45, as illustrated at 50, is one end of an adjustable link 51, the opposite end of which is pivotally connected as at 52 to one arm 53 of a bell-crank lever 54. The bell-crank lever 54 is pivoted at 55 to a bracket 56 secured to the table 3.

Pivotedly attached to the outer end of the second arm 57 of the bell-crank lever 54 is one end of a link 59, the opposite end of which is pivoted as at 60 to a lever 61. The lever 61 is pivotally mounted, as at 62, to the frame 1 and is provided with a cam-follower 63 which is adapted to ride on the peripheral surface of a cam 64 carried by a cam drum 65 which, in the present instance, is secured to a shaft 66. The shaft 66, in the type of machine to which the invention is applied in the present instance, is designated as the striping cam shaft.

As the drum 65 is rotated, for example, in the direction of the arrow illustrated in Fig. 11, the cam-follower 63 will ride the stepped cam 64 and thereby move the trailer cam 32 radially with respect to the needle cylinder 4. The needle-raising cam 26 at the same time is adapted to be moved radially with respect to the needle cylinder 4 by means of a stepped cam 67 carried on the periphery of the cam drum 65.

Co-operating with the cam drum 65 and the stepped cam 67 thereon is a cam-follower 68 carried on one end of a lever 69 which is pivotally mounted on the stud 62 on which the lever 61 is mounted.

Pivotally mounted at 69a on the opposite end of the lever 69 is one end of a link 70, the opposite end of which is pivotally connected as at 71 to one arm 72 of a bell-crank lever 73. The bell-crank lever 73 is pivotally mounted at 74 on a bracket 75 secured to the table 3.

To the second arm 76 of the bell-crank lever 73, at the point 77, is pivotally connected one end of the link 78, the opposite end of which is pivotally connected at 79 to the outer end of the stem 36 of the raising cam 26.

In accordance with the arrangement of the steps of the cams 64 and 67 on the drum 65 and their relation with respect to each other the raising and lowering cams 26 and 32 respectively will be moved in unison upon rotation of the drum 65 in a manner to produce the superposed design illustrated in Fig. 16. Obviously, by changing the relation of the steps of the cams 64 and 67 the cams 26 and 32 may be moved separately and by making the peripheral surface of the cam 64 continuous on one radius and permitting the cam-follower 63 to ride on the continuously circular peripheral surface of the cam 64 the lowering

cam 32 may be held inoperative, as in producing the superposed designs shown in Figs. 18 and 20.

From the above, it will be obvious that by rotating the drum 65 in timed relation to the rotation of the needle cylinder 4 predetermined needles carried by the said cylinder may be raised and lowered with respect to the cylinder to take or not to take the plating thread z from the thread guide 31 as desired, in order to form a superposed design on the foundation fabric being normally knit by the full complement of needles carried by the needle cylinder 4.

In the conventional type of machine to which the invention is applied in the present instance, it is desirable, during the formation of the superposed design, to take out of action one of the normal or regular stitch-forming cams of the machine; for example, the cam assembly including the cams 11, 12, 13 and 14 is provided for normal operation during both the continuous circular knitting of the leg and foot and the knitting of the heel and toe as produced by relative oscillatory movement between the cylinder 4 and the cam assembly, including the cams 11, 12, 13 and 14.

During the regular circular knitting of the leg and foot portions of the stocking, the regular butts 10 of the needles 9, in moving in a direction indicated by the arrow c in Fig. 10, with respect to the cam assembly 11, 12, 13 and 14, would be raised by the upper point 13a of the cam 13, to cause the loops that are held by the needles 9 to clear the latches of the needles, the needles being subsequently lowered by the cam 12 engaging the butts 10, to take thread in the hooks of the needles from a pair of thread guides 80 and 81 respectively, and to insure that the loops held by these needles are in position behind the latches to properly form the new loops by the threads taken from the guides 80 and 81 as the needles are lowered to cast their previously held loops by the cam 14, the needles subsequently being raised to their leveled position a by the butts 10 riding upwardly on the inclined face 15a of the leveling cam 15.

In forming the superposed design in accordance with the present invention the latch clearing raising of the needles by the point 13a of the cam 13 is undesirable, therefore, the cam 13 is so constructed as to be moved radially outward so as not to be engaged by the butts 10 of the needles 9. For this purpose, the cam block 16 and cam 13 are constructed and assembled in the manner illustrated in Figs. 14 and 15; that is, the cam block 16 is provided with a circular bore 82 in which is slidably mounted a circular rod 83 to which the cam 13 is secured by means of screws 84.

In order to take the cam 13 out of action, during the knitting of the leg and foot portions of the stocking in which the superimposed design is formed by the mechanism constituting the present invention, to the outer end of the rod 83 is pivotally connected, as at 85, one end of a link 86, the opposite end of which is pivotally connected at 87 to one arm 88 of the bell-crank lever 89. The bell-crank lever 89 in the present instance is pivotally mounted at 91 to an upright member 90 which supports the latch ring 92, which in turn supports the thread guides 31, 80 and 81 and the thread clamp and shearing device 30.

To the outer end of the second arm 93 of the bell-crank 89 is pivotally connected, as at 94, one end of a link 95, the opposite end of which is

pivotally connected at 96 (see Fig. 11) to one end of a lever 97. The lever 97 is pivotally mounted on a stud 98 secured in the main frame 1 of the machine. The opposite end of the lever 97 is provided with a cam-follower 99 which is adapted to be engaged by cams 100 and 101 carried by a drum 102 which normally controls the action of the thread guides 31, 80 and 81.

The drum 102, in effect, is a measuring drum, as it receives one complete revolution for each stocking produced by the machine and controls the timing of the continuous circular movements of the cylinder 4, during the knitting of the leg and foot portions of the stocking, and the oscillatory movement of the cylinder, during the knitting of the heel and toe portions of the stocking.

During the said knitting of the leg and foot portions of the stocking, the cam-follower 99 is engaged by the cams 100 and 101 respectively which, through the mechanism above described, slides the cam 13 radially outward with respect to the cylinder 4 to such an extent that the said cam is not engaged by the butts 10 of the needles 9, whereupon the butts 10 will follow through in a horizontal plane from the leveling surface 15b of the cam ring 15, the said butts 10 passing under the low point of the triangular cam 12, which normally lowers the needles after they have been raised by the point 13a of the cam 13 to insure the clearing of the latches by the loops held on the needles.

It will be here noted that the needles that have been raised by the cam 26 and which have not been lowered by the trailing cam 32 are lowered by the triangular cam 12 after they have taken their thread from the thread guide 31 and before they take thread from the thread guide 80, 81, or both, prior to the lowering of the needles by the stitch cam 14, which causes the needles to cast the loops previously held thereby.

Ordinarily the needles after passing under the stitch cam 14 ride up the inclined surface 15a of the cam 15 to draw the newly formed loops down over the latches to open the latches for the reception of the threads to form the next course of loops and leave the inclined surface 15a in the plane of the leveling surface 15b, as illustrated by the broken line 15c in Fig. 10.

In order to cause the newly formed loops to clear the latches when the cam 13 is moved to an inoperative position a supplementary cam 15d is provided, having an inclined surface 15e which is contiguous with the inclined surface 15a of the cam 15, and rises above the leveling surface 15b a sufficient distance to cause the needles to be raised high enough for the loops held thereby to clear the latches. The needles are then brought down to the leveling surface 15b to position the loops behind the latches by a cam 115 having an inclined surface 115a which engages the upper edges of the butts 10 of the needles 9 and thereby moves the needles downwardly until the said butts again rest on the leveling surface 15b.

When the stitch cam 13 is taken out of action, it is also desirable to take out the needle picker 18 and for this purpose the needle picker 18 is provided with an outwardly projecting pin 118 which is adapted to be engaged by a lug 113 on the stitch cam 13, as clearly illustrated in Figs. 14 and 14.

There may be times during the normal operation of the machine when it may be desirable to have the striping cam shaft 66 in operation, when it is not desired to have the raising and

lowering cams 26 and 32, which are controlled by the cam drum 65, operating to produce superposed designs on the fabric. In order to hold the cams 26 and 32 out of action at such times 5 the following mechanism is provided:

The cam drum 102 is secured to a shaft 120 which is journaled in the frame 1 of the machine, and on one end of this shaft is a drum 121 which, in the present instance, provides a mounting for 10 release cams 122 and 123. The cam 122 functions to release the design-forming cams 26 and 32 during the formation of the leg of the stocking, while the cam 123 functions to release the design-forming cams 26 and 32 during the formation of 15 the foot portion of the stocking.

The release cams 122 and 123 are adapted to engage a cam-follower 125 on a lever 126 that is pivotally mounted at 127 on a bracket 128 secured to the frame 1 of the machine, the cam-follower 20 125 being held in engagement with the peripheral faces of the cam segments 122 and 123, or the peripheral surface of the drum 121, by means of the spring 129 having one end anchored at 130 to the rigid portion of the machine while the opposite end of the spring is connected at 131 to one end of the lever 126.

Pivotally attached at 132 to the lever 126 is one end of a link 133, the opposite end of the said link being pivotally attached at 134 to one arm 30 135 of a bell-crank lever 136. The bell-crank lever 136 is pivotally mounted at 137 on a bracket 138 secured to the table 3 of the machine.

Attached to the second arm 139 of the bell-crank lever 136 at 140 is one end of a link 141, the opposite end of which is provided with an elongated slot 142 for the reception of the pin 143 that is carried by the outer end of the arm 76 of the bell-crank lever 73, which normally controls the actuation of the raising cam 26. The 40 spring 144, which has one end connected to the arm 76 of the bell-crank lever 73 and its opposite end connected to a post 145 extending upwardly from the table 3, normally tends to rock the bell-crank lever 73 and through the connecting mechanism move the raising cam 26 towards the cylinder 4 into an operative position with respect to the butts 21 of the needle-extensions 20. This spring also tends to rock the lever 69 about its 45 pivot 62 to press the cam-follower 68 toward the drum 65.

When the cam-follower 68 is in engagement with the peripheral surface of the drum 65 the raising cam 26 is in its closest possible position with respect to the needle cylinder 4, the steps of 50 the cam 67 determining the position of the cam 26 with respect to the butts 21a, 21b and 21c of various lengths, to be actuated by the cam 26. The greater the distance between the engaging end of the cam-follower 68 and the peripheral 55 surface of the drum 65 the greater the distance between the innermost edge of the cam 26 and the peripheral surface of the needle cylinder 4. Thus, when the cam-follower 125 of the lever 126 moves to a position in engagement with the peripheral surface of the drum 121, the lever 126 will pull the link 133 downwardly thereby rocking the bell-crank lever 136 and moving the link 141 to the right, as viewed in Fig. 2, whereby the end 146 of the slot 142 in said link will engage the pin 143 of the bell-crank lever 73, rocking said bell-crank about its pivot, and through the link 78 pulling the cam 26 to its outermost or inoperative position and at the same time lowering the 70 link 70 and rocking the lever 69 about its pivot 62 to raise the cam-follower 68 clear of the stepped cam 67 on the drum 65.

At the same time the lowering cam 32 is taken out of action by a link 150, one end of which is pivotally connected at 151 to the lever 126, the opposite end of the link 150 being pivotally connected at 152 to one arm 153 of the bell-crank lever 154. The bell-crank lever 154 is pivoted at 155 to a bracket 156 mounted on the table 3. Pivotally attached to the second arm 157 of the bell-crank lever 154 is one end of a link 158. The opposite end of the link 158 is pivotally connected at 159 to the lever 45 which controls the actuation of the lowering cam 32.

The link 158 is of a telescopic nature having one section 160 connected to the lever 45 while the other section 161 is connected to the bell-crank lever 154 and slides within the element 160, as illustrated in Fig. 3. The section 161 of the telescopic link 158 is in the form of a rod and is provided with the collar 162 which, when the cam-follower 125 of the lever 126 rides off the release cams 122 or 123 onto the peripheral surface of the drum 121, engages the end 163 of the section 160. Continued movement by the section 161 under the influence of the spring 165 rocks the lever 45 about its pivot 46 and thereby withdraws the lowering cam 32 to an inoperative position beyond the extreme outer end of the longest but 21c.

The springs 165 and 129 normally hold the cam-follower 125 in contact with either the peripheral surface of the drum 121 or the peripheral surfaces of the release cams 122 and 123 carried by the said drum 121.

A spring 166 having one end secured to a collar 167 and its opposite end secured to the lever 45 provides a resilient connection between the arm 45 and the section 161 of the telescopic link 158. The spring 166 through the link 51, bell-crank 115 54 and link 59 holds the cam-follower 63 of the lever 61 in operative engagement with the cam 64 or the peripheral surface of the drum 65 on which said step cam is mounted, and when the lever 45 is rocked to move the lowering cam 32 120 to its inoperative position the cam-follower 63 is raised to a high position clear of the cam 67 on the drum 65.

The holding out of the cams 26 and 32 in the manner above noted is effected at the time the cylinder 4 is normally oscillating to produce the heel and toe of the stocking and so that the cams 26 and 32 will in no way interfere with this operation.

As shown in Fig. 4, the relation of the thread guide 31 with respect to the thread guides 80 and 81 is such that the thread *z* controlled by the thread guide 31 extends at such an angle from the thread clamp 30 to the thread guide 31 as to permit the needles normally riding in the leveled plane *a* to pass under the plating thread *z*, while the needles which have been raised by the cam 26 to the position *b* cross the plane of the thread *z* and thereby take this thread as the needles pass the thread guide 31. The threads *x*, *y* which are respectively controlled by the thread guides 80 and 81 extend at such an angle from the thread clamp 30 to the said thread guides that the needles in position *a* will cross the plane of these threads and take thread from the thread guides as the needles pass the same.

The thread guides 31, 80 and 81, and others, are controlled from the pattern drum 102 in the usual manner, through cams 170, on the drum 102, co-operating with arms 171 which are piv-

totally mounted on the fixed stud 98, and through wires 172 and actuating levers 173, which in turn rock the thread guides to operative or inoperative positions about a pivot rod 174, against the action 5 of flat strings 175, which normally tend to lower the outer ends of the thread guides into a position to deliver thread to the needles as the needles pass by the thread guides.

Normally the striper cam drum 65 is adapted 10 to actuate the thread guides for producing horizontal stripes in the stocking, through levers similar to the levers 61 and 68, which have forked ends that pass around the controlling wires 172, where these wires connect with the controlling 15 levers 170, but in carrying out the principles of the present invention the function of the striping cam drum 65 is to control the actuations of the design-forming cams 26 and 32. Hence the substitution of the levers 61 and 69 for those which 20 normally co-operate with the wires 172 to control the thread guides of the machine.

The cam drum 65 is adapted normally to be advanced intermittently, one step for each course of stitches produced. In carrying out the principles of this invention this intermittent rotation 25 of the drum 65 is utilized to set the cams 26 and 32 for each course of stitches produced, in order to produce the desired outline on the design being superimposed upon the knitted fabric.

30 The intermittent rotation of the drum 65 is obtained in the usual manner from the gear wheel 180 which, as shown in the above-mentioned patent, is geared to the main drive shaft of the machine in four-to-one ratio and functions as the crank for producing the oscillatory motion of the needle cylinder during the knitting of the heel and toe portions of the stocking.

Extending laterally from the gear 180, at 90 40 degree intervals, are rollers 181 which are adapted to engage a lever 182 that is pivoted at 183 to the table 3 and is provided at its lower end with a pawl 184 which is adapted to engage the teeth of a ratchet wheel 185 that is secured to the shaft 66 on which the cam drum 65 is 45 mounted. Outward drum-advancing movement of the lever 182 is provided by engagement of the rollers 181 successively with the lever 182, while return movement of the lever is effected by means of a spring 185. Thus the drum 65 is advanced one step for each revolution of the 50 needle cylinder 4 during the continuous circular movement of the said cylinder.

During the knitting of the heel and toe portions, advancement of the drum 65 is not desired, 55 therefore, the lever 182 is moved to and held at an outward position beyond the path of movement of the actuating rollers 181. The holding of the lever 182 in its inoperative position is effected by a laterally extending lug 186 formed 60 on a lever 187 that is pivotally mounted at 188 on the end of the striping shaft 66. At a point 189 intermediate the ends 187 is pivotally connected one end of an adjustable link 190, the opposite end of which is pivotally connected at 191 65 to one end of a lever 192. The lever 192 is pivoted at a point 193 intermediate its ends to the frame 1. Pivoted on the opposite end of the lever 192, at the point 194, is one end of a link 195, the opposite end of which is pivoted at 196 to a 70 chain rider 197, the chain rider in turn being pivoted at 198 to the frame 1.

The chain rider 197 is adapted to be engaged by a series of lugs 199 formed on one side of the links of a controlling chain 200. The chain 75 200 passes around a sprocket wheel 201 (see

Fig. 2) which is rotatably mounted on the shaft 120 and is secured to a ratchet wheel 202 which is intermittently moved or rotated one step at a time, by mechanism shown in the above-mentioned patent, to bring the lugs 199 successively 80 under the chain rider 197, to swing the chain rider about its pivot which, through the link and lever mechanism just described, swings the lever 187 about its pivot to move the lug 186 of the lever 187 away from the pawl-carrying lever 182, so that the lever 182 may be actuated to 85 rotate the drum 65 in the manner above noted.

The lever 187 when swung to the inoperative position just noted is held in such inoperative position by a latch 203 having a shoulder 204 which drops behind the lever 187 and thereby holds the lug 186 away from the lever 182. The latch 203 is pivoted at 205 to the frame 1 of the machine.

As long as the latch 203 retains the lever 187 in an inoperative position the lever 182 will be operated to rotate the drum 65 to bring the various steps of the cam 64 and the cam 67 under the cam-followers of the levers 61 and 69, to operate the raising and lowering cams 26 and 32 to form 95 a design in accordance therewith.

Mounted on the shaft 66 with the drum 65 is a sprocket wheel 206, around which passes the chain 207 having lugs 208 which are adapted to engage a toe 209 on the latch 203, to raise the 105 latch to such an extent that the shoulder 204 will release the lever 187, the said lever 187 in turn swinging about its pivot under the influence of the spring 210 to cause the lug 186 to again engage the pawl-carrying lever 182 to 110 move said lever to an inoperative position whereby the drum 65 will not be rotated and consequently the cams 26 and 32 will remain in the 115 position to which they have been last moved. In so doing, the cams 26 and 32 will continue to form lines of plated stitches walewise of the 120 fabric being knit, until another of the lugs 199 on the chain 200 engages the chain rider 197 and thereby moves the lever 187 to the inoperative 125 position above described, whereby the latch 120 203 will hold the lever 187 in its inoperative position until another of the lugs 208 on the chain 207 releases the said latch from the lever 187.

From the above, it will be obvious that by arranging the lugs 199 on the chain 200 and the 125 lugs 208 on the chain 207 in a predetermined manner the form of design produced by the actuation of the cams 26 and 32 may be widely varied.

The pattern drum 102, as in the patent above noted, is rotated intermittently by a ratchet wheel 211, and, with the drum 102, the ratchet wheel 211 and the drum 121 being secured to the shaft 120, the timing of the operation of the cams 26 and 32 is regulated in accordance with the knitting of the portions of the stocking which are to receive the superimposed design as formed by the actuations of the cams 26 and 32.

As the mechanism that forms the primary design, by a reverse plating method, forms no part of the present invention, no further reference to such mechanism will be made in the present application as it will be obvious from the above that the mechanism forming the subject of the present invention is applicable to a machine which produces ordinary plain circular knit 145 fabric.

I claim:

1. The combination with the needles and stitch cams of a knitting machine, of butts of various lengths associated with predetermined needles, a 150

- selector cam movable lengthwise of the various length butts to selectively raise needles to form a design on the fabric being knit by normal co-operation between the needles and stitch cams, and a rectifying cam following said selector cam and movable lengthwise of the various length butts for selectively lowering raised needles to cancel predetermined portions of the selection made by the selector cam.
2. The combination with the needles and stitch cams of a knitting machine, of butts of various lengths associated with predetermined needles, a selector cam movable lengthwise of the various length butts to selectively raise needles to form a design on the fabric being knit by normal co-operation between the needles and stitch cams, a rectifying cam following said selector cam and movable lengthwise of the various length butts for selectively lowering raised needles to cancel predetermined portions of the selection made by the selector cam, and means for moving said selector cam lengthwise of the butts to give shape to the design.
3. The combination with the needles and stitch cams of a knitting machine, of butts of various lengths associated with predetermined needles, a selector cam movable lengthwise of the various length butts to selectively raise needles to form a design on the fabric being knit by normal co-operation between the needles and stitch cams, a rectifying cam following said selector cam and movable lengthwise of the various length butts for selectively lowering raised needles to cancel predetermined portions of the selection made by the selector cam, and means for moving said rectifier cam lengthwise of the butts to give shape to the design.
4. The combination with the needles and stitch cams of a knitting machine, of butts of various lengths associated with predetermined needles, a selector cam movable lengthwise of the various length butts to selectively raise needles to form a design on the fabric being knit by normal co-operation between the needles and stitch cams, a rectifying cam following said selector cam and movable lengthwise of the various length butts for selectively lowering raised needles to cancel predetermined portions of the selection made by the selector cam, and means for moving the selector and rectifier cams lengthwise of the butts in unison to give shape to the design.
5. The combination with the needles and stitch cams of a knitting machine, of butts of various lengths associated with predetermined needles, a selector cam movable lengthwise of the various length butts to selectively raise needles to form a design on the fabric being knit by normal co-operation between the needles and stitch cams, a rectifying cam following said selector cam and movable lengthwise of the various length butts for selectively lowering raised needles to cancel predetermined portions of the selection made by the selector cam, means for moving the selector cam lengthwise of the butts, means for moving the rectifier cam lengthwise of the butts, and means for moving said cams to inoperative positions relative to said butts.
6. The combination with the needles and stitch cams of a knitting machine, of butts of various lengths associated with predetermined needles, a selector cam movable lengthwise of the various length butts to select needles to form a design on the fabric being knit by normal co-operation between the needles and stitch cams, a rectifying cam following said selector cam and movable lengthwise of the various length butts for canceling predetermined portions of the selection made by the selector cam, actuating means including a prime mover for moving the selector cam lengthwise of the butts, actuating means including a prime mover for moving the rectifier cam lengthwise of the butts, and means for disengaging said actuating means from said prime movers.
7. The combination with the needles and stitch cam assembly of a knitting machine, of means for selectively operating predetermined needles to form a design on the fabric being knit by normal co-operation between said stitch cam assembly and said needles, and means co-operating with said needle-selecting means for taking one of the cams of said assembly out of action during the formation of the design by said needle selection.
8. The combination with the needles, needle pickers, and stitch cam assembly of a knitting machine, of means for selectively operating predetermined needles to form a design on the fabric being knit by normal co-operation between said stitch cam assembly and said needles, and means co-operating with said needle-selecting means for taking one of the cams of said assembly and a needle picker out of action during the formation of the design by said needle selection.
9. The combination with the needles and stitch cams of a knitting machine, of means for selectively raising predetermined needles and means for selectively lowering certain of the selectively raised needles to form a design on the fabric being knit during the formation of one portion of the fabric by normal co-operation between the stitch cams and needles, and means for taking the needle raising and lowering means out of action simultaneously during the knitting of another portion of the fabric.
10. The combination with the needles and stitch cams of a knitting machine, of means for selectively operating predetermined needles to form a design on the fabric being knit during the formation of one portion of the fabric by normal co-operation between the stitch cams and needles, means co-operating with the needle-selecting means for taking certain of the normal stitch cams out of action during the formation of that portion of the fabric including the design produced by said needle selection, and means for taking the needle-selecting means out of action during the knitting of another portion of the fabric.
11. The combination with a needle support having grooves and needles therein, of needle extensions associated with predetermined needles in said grooves, butts of various lengths extending laterally from the respective needle-extensions, a cam normally disposed in an outer position beyond the longest of said butts and adapted to be moved to an inner position adjacent the said support to be engaged by all the butts, means for positioning said cam at points intermediate said outer and inner positions to select predetermined butts for engagement with said cam for advancing the needles controlled thereby to operative positions relative to the remainder of the needles in said support, and a retracting cam following said advancing cam and movable substantially parallel thereto to engage predetermined butts advanced by said advancing cam to retract the needles controlled thereby to an inoperative position.
12. The combination with a needle support having grooves and needles therein, of needle extensions associated with predetermined nee-
